UNITED STATES PATENT OFFICE.

JOSEPH G. AYERS, OF MONTCLAIR, NEW JERSEY, ASSIGNOR TO GENERAL MOTORS CORPORATION, OF DETROIT, MICHIGAN, A CORPORATION OF DELAWARE.

QUENCHING APPARATUS.

Application filed March 14, 1924. Serial No. 699,380.

To all whom it may concern:

Be it known that I, JOSEPH G. AYERS, a citizen of the United States, residing at Montclair, county of Essex, State of New Jersey, have invented a certain new and useful Quenching Apparatus, of which the following is a full, clear, and exact description, such as will enable others skilled in the art to which it appertains to make and use 10 the same, reference being had to the accompanying drawings, forming part of this specification.

This invention relates to quenching apparatus and is herein shown as embodied in 15 apparatus for clamping hollow articles such as rings or sleeves during a quenching operation.

In the manufacture of race rings for roller bearings, it is customary to confine the 20 hot work pieces on a suitably shaped core or plug to prevent distortion of the work pieces while quenching in a bath of cooling fluid. If such plugs are of a diameter to just fit the hot work pieces, they can not be inserted with facility and, if they are 25 small, they do not properly support the work pieces during the quenching operation. It has been proposed to expand a member within the work pieces but such fixtures 30 have not had a sufficiently large outer surface to hold the work against distortion nor have they maintained the proper shape during all positions of expansion.

It is an object of this invention, therefore, 35 to provide an apparatus which will avoid the above and other disadvantages. In accordance with one feature, a solid core in the form of a pyramid or frustum of a pyramid cooperates with a series of outer sections having correspondingly inclined flat faces fitting the pyramidal faces, the sections presenting a substantially continuous outer holding surface which is expanded within the work by relative sliding 40 movement of the flat faces upon one another. In the illustrated construction, the sections are moved longitudinally on the pyramidal faces by cooperating cam members and the cylindrical surface maintains its shape in 45 all positions of adjustment.

To these ends and also to improve generally upon devices of the character in-

dicated my invention consists in the various matters hereinafter described and claimed.

Referring to the drawings, Figure 1 is a 55 front elevation of the quenching apparatus.

Figure 2 is a front elevation of the core.

Figure 3 is an end view of the core.

Figures 4 and 5 are, respectively, a front and a side view of one of the clamping sec- 60 tions.

Figure 6 is an end view of two adjacent clamping members looking at their larger ends.

Figure 7 is a modification partly broken 65 away and in section.

The numeral 10 designates a support which can be raised and lowered to carry the apparatus into and out of a bath of liquid to quench an article. A vertically extend- 70 ing shaft 12 is fastened to the support 10 by a set screw 14 and to take the upward thrust to which the shaft is subjected in operation, a nut 16 is threaded on the lower end of the shaft and abuts against a washer 75

on the underside of the support 10. The upper end of the shaft has a reduced threaded portion 18 which screws into an opening in the small end of a core 20, the core preferably being substantially of the 80 form of a frustum of a pyramid, herein shown as having eight flat pyramidal faces 22. The flat faces are relieved at intervals as indicated at 24 by means of peripheral cuts, thus reducing the area of the flat faces 85 on which clamping members, to be herein- after referred to, may slide easily. Extending longitudinally at each pyramidal face 22 is a keyway or slot 26 arranged to receive a longitudinal key 32 projecting from an 90 inclined flat face 30 on an outer clamping section 28 to guide the latter for longitudinal movement. The clamping sections are of substantially sectoral form at their larger 95 ends and of substantially segmental form at their smaller ends and their outer surfaces form a substantially continuous cylindrical face to grip the interior of a hollow article. In Figure 1, the sections 28 are shown in their fully expanded positions in 100 which they are slid upwardly as far as they will go upon the central core. By the use of a pyramidal core and complementary flat faces on the clamping sections, the sections

present a true cylindrical surface in all positions of expansion. Moreover, contact of the quenching fluid with the interior surface of the article can be prevented when it is not desirable to harden that surface.

At the wider ends of the clamping sections, there are extensions 34 extending parallel to the axis of the core and surrounding the shaft 12. Each clamping section 10 has a series of slots 36 in its periphery to receive split spring rings 38 which tend to collapse the sections and force them towards the core when they are moved to the small end of the latter. At their upper ends, the 15 sections are recessed as at 40 to receive a flange 39 on an upper retaining ring which is sleeved over a cylindrical extension 41 on the core, the ring being retained on the core by a disc 42 fastened on the extension 20 41 by a screw. The larger ends of the sections extend into an opening in a lower limit ring 44 and the bases of the sections rest against a ring 46 which enters a circular recess in the lower 25 limit ring. The ring 46 may be fastened to or be an integral flange on a rotary member 48 having an operating handle 50. Fixed to the underside of the member 48 and surrounding the shaft 12, is a cam member 30 52 arranged to cooperate with a relatively fixed cam member 54 formed on a collar 56 secured to the support 10. A limit pin 58 fixed to the rotary member 48 engages another limit pin 60 on the collar 56 and limits the swinging movement of the 35 rotary member. At their upper ends, the clamping members are chamfered or beveled as at 62 to facilitate slipping a hollow article over them. When the article is to be hardened on the inside as well as the outside, longitudinal or helical grooves (not shown) are formed in the outer surfaces of the 40 clamping members and these grooves communicate with radial slots 64 in the lower limit ring 44 so that liquid which enters the longitudinal grooves when the apparatus is lowered into the liquid, can flow out under the hollow article, through the radial 45 slots, when the apparatus is raised.

50 In operation, the heat treated sleeve or ring is slipped down over the clamping sections when the latter are in their contracted positions. Then the handle is turned to the position shown in Figure 1 whereby the 55 cooperating cam members 52 and 54 cause the member 48 and its integral ring 46 to be elevated against the bases of the clamping sections 28 and the latter are moved longitudinally of the core, their flat faces 60 30 being guided along the faces 22 of the core by the keys 32. This expands the sections and grips the work. The fixture, including the support 10, is then lowered into the quenching liquid and when the article 65 is quenched the fixture is raised. The handle

50 is again turned, in the other direction, to allow the clamping sections to drop and, during this movement, the split spring rings 38 cause the clamping sections to move inwardly towards the core in readiness to receive another article. By removing the split spring rings 38 and raising the upper limit ring 39, the clamping sections can be removed and replaced by others.

70 In the form shown in Figure 7, there is 75 shown a core having pyramidal faces 70 engaged by complementary faces on a series of clamping sections 72 which are retained and pressed towards the core by split spring rings 74. Integral with, or attached to, the 80 larger end of the core is a screw 76 cooperating with interior threads on a nut 78 having a turning handle 80 and rotatable in an annular recess 82 in a base 84. A shaft 86 extends upwardly through the base, 85 through the screw and core and is provided at the ends with washers and nuts to hold the parts together. An upper limit ring 88 is sleeved on the shaft also and has a 90 downwardly extending circular flange engaging shoulders on the clamping sections to limit their outward movement. A lower limit ring 90 surrounds the lower ends of the clamping sections and rests on a locking ring 92 having a key slot 94 to receive 95 a locking key passed through any one of a series of radially extending slots in the base member.

100 In the operation of the modification, the turning of the handle 80 and the nut 78 elevates the screw and the core along the shaft 86 and causes the clamping sections to be spread to the position shown. Moving the handle in the other direction depresses the core which slides downwardly 105 on the shaft 86 and the sections are then collapsed by means of the spring rings.

110 Although the invention has been described by reference to specific constructions, it should be understood that, in its broader aspects, it is not necessarily limited to the 115 illustrative embodiments thereof.

I claim:

1. In a quenching apparatus, a core having a series of outer pyramidal faces, a 115 series of clamping sections having inner pyramidal faces, the clamping sections providing a substantially continuous outer clamping surface, and means for causing a relative longitudinal movement between the 120 core and the clamping sections; substantially as described.

2. In a quenching apparatus, a core having a series of outer pyramidal faces, a 125 series of clamping sections having inner pyramidal faces, the clamping sections forming a substantially continuous cylindrical surface and means for causing a relative movement of the core and the clamping sections; substantially as described.

3. In a quenching apparatus, a core in the form of a frustum of a pyramid, a plurality of complemental outer sections each having an inclined flat face fitting one of the flat faces of the frustum, and means for relatively moving the frustum and the sections; substantially as described.
4. In a quenching apparatus, a core in the form of a frustum of a pyramid, a plurality of complemental outer sections each having an inclined flat face fitting one of the flat faces of the frustum, said outer sections presenting a substantially continuous outer surface, to enter a hollow article, and means for relatively moving the frustum and the sections to spread the latter; substantially as described.
5. In a quenching apparatus, a core in the form of a frustum of a pyramid, a plurality of complemental outer sections each having an outer groove and an inclined flat face fitting one of the flat faces of the frustum, and a spring ring fitting in the grooves of the sections to hold them together; substantially as described.
6. In apparatus of the character described, a core in the form of a frustum of a pyramid, a plurality of complemental outer sections each having an inclined flat face fitting one of the flat faces of the frustum, means for guiding the outer sections along the faces of the frustum, and means for causing a relative movement of the frustum and the sections; substantially as described.
7. In apparatus of the character described, a core in the form of a frustum of a pyramid, a plurality of complemental outer sections each having an inclined flat face slideable on one of the flat faces of the frustum, means for guiding the outer sections along the faces of the frustum, means for pressing the sections toward a center, and means for spreading the sections; substantially as described.
8. In apparatus of the character described, a core in the form of a frustum of a pyramid, a plurality of complemental outer sections each having an inclined flat face slideable on one of the flat faces of the frustum, longitudinal keys between the faces of the frustum and the outer sections, and means for sliding the sections along the frustum; substantially as described.
9. In apparatus of the character described, a core having a plurality of flat inclined faces, a plurality of complemental outer sections having inclined flat faces fitting the flat faces of the core, said outer sections being of sectoral form and presenting a substantially continuous outer surface, and means for relatively moving the core and the sections; substantially as described.
10. In apparatus of the character described, a core in the form of a frustum of a pyramid, a plurality of outer sections each having an inclined flat face fitting one of the flat faces of the frustum, and cam members associated with the core and the sections for relatively moving them along their inclined flat faces; substantially as described.
11. In apparatus of the character described, a core having a plurality of flat inclined faces, a plurality of complemental outer sections having inclined flat faces fitting the flat faces of the core, a cam member fixed with respect to the core, and a second cam member engaging the first cam member and the outer sections to spread the latter; substantially as described.
12. In apparatus of the character described, a core in the form of a frustum of a pyramid, a plurality of outer sections each having an inclined flat face fitting one of the flat faces of the frustum, a shaft extending from the frustum, a cam member fixed with respect to the shaft, and a cam member loose on the shaft and movable thereon to spread the sections; substantially as described.
13. In apparatus of the character described, a core in the form of a frustum of a pyramid, a plurality of outer sections each having an inclined flat face fitting one of the flat faces of the frustum, a shaft connected to the small end of the frustum, a cam member fixed with respect to the shaft, and a cam member slideable and rotatable on the shaft to slide the outer sections along the core; substantially as described.
14. In apparatus of the character described, an elevating support, a shaft extending upwardly from the support, a frustum of a pyramid attached at its small end to the shaft, a plurality of outer sections each having an inclined flat face slideable along one of the flat faces of the frustum, means for holding the sections together, and means for sliding the sections longitudinally; substantially as described.

In testimony whereof I hereunto affix my signature.

JOSEPH G. AYERS.
